[57] CLAIM

The ornamental design for an abrading tool blade, substantially as shown and described.

DESCRIPTION

FIG. 1 is a front elevational view of an abrading tool blade showing our new design;

FIG. 2 is a left end elevational view thereof;

FIG. 3 is a front elevational view of a modified embodiment of FIG. 1;

FIG. 4 is a left end elevational view thereof;

FIG. 5 is an enlarged perspective view of FIG. 1; and

FIG. 6 is an enlarged perspective view of FIG. 3.
